UNITED STATES PATENT OFFICE.

EZRA C. ALE, OF ALTOONA, PENNSYLVANIA.

RAILWAY-RAIL JOINT.

No. 865,561.

Specification of Letters Patent. Patented April 21, 1908.

Application filed May 27, 1907. Serial No. 375,856.

To all whom it may concern:

Be it known that I, EZRA C. ALE, a citizen of the United States, residing at Altoona, in the county of Blair and State of Pennsylvania, have invented certain new and useful Improvements in Railway-Rail Joints, of which the following is a specification.

My invention relates to certain new and useful improvements in joints for railway-10 rails.

The prime object of my invention is to provide a strong, durable and reliable rail joint, so constructed and assembled, as to reduce to a minimum the liability of the spreading of 15 the rails at the meeting ends thereof.

A further object is to dispense with the use of bolts and nuts in assembling and securing the several parts constituting the joint.

Another object of this invention is to save 20 the expense and labor due to the boring or punching of a series of holes through the web of the rail near the meeting end thereof, which practice is now commonly employed, for the reception of bolts or other similar 25 securing means, thereby keeping the rail intact and maintaining its solidity at a point where the greatest strength is required.

The foregoing and such other objects as may occur from the ensuing description are 30 attained by the combination, arrangement and location of parts illustrated by the accompanying drawings, and particularly pointed out in the appended claims.

Referring to the drawings:—Figure 1 represents in side elevation the improved rail joint embodying my invention. Fig. 2 illustrates a cross-sectional view taken on the line x—x, Fig. 1. Figs. 3 and 4 respectively, 35 are perspective views of the securing keys forming a part of my invention, and Fig. 5 is a perspective view of the combined base and bridge plate.

Like numerals of reference designate corresponding parts throughout the several 45 views of said drawings.

Referring now to Fig. 1, the numerals 1, 1', 50 represent wooden railway ties arranged at a suitable distance apart, and secured to the upper surface thereof by spikes or other desirable means is a combined base and bridge-plate 2. The upper surface 2' of said bridge-plate, between its upwardly projecting side-walls 3, 3', is adapted to receive and support the meeting ends of the rails 4, 4', said rails

being formed with a shouldered web portion 55 as clearly shown by dotted lines.

In securing the rails 4, 4', together in proper alignment I employ fish-plates or bars 5, 5', adapted to engage the upper surface of the base of the rails, the web portion thereof and the under surface of the head or tread of the rails. The outer surface of each fish-bar or plate is gradually inclined outwardly from the upper to the lower portion thereof, and each is provided with a plurality of recesses 6, adapted to receive one of the securing keys 7, which engages with a key 8, said keys 7 and 8, and their functions being hereinafter more fully described.

The lower portion of the bridge-plate 2, 70 is provided with shoulders 9, 9', which rest against the inner side of each of the ties 1, 1', respectively, near the upper portion of the same, thus maintaining, in connection with the securing means, all of the several parts in 75 their proper relation one to the other. The said combined base and bridge plate 2, is also provided with openings 10, at each side through which are passed the securing keys 7 and 8.

The exterior lower surface of the fish-plate or bars 5, 5', at all points not recessed, is so fitted as to contact firmly with the inner surface of the walls 3, 3', of the bridge-plate 2, thus rigidly holding the fish-plates in contact 85 with the rails and thereby preventing lateral displacement or movement of both the rails and fish-plates. The key 8, which is adapted to pass through the openings in the plate 2, is made of steel, and its lower end is provided 90 with an outwardly projecting head 13, which engages the lower surface of the combined base and bridge-plate 2, such head serving to prevent upward movement of the key, and at a point intermediate of the length of said key 95 8, is another outwardly projecting lug 14, adapted to contact with the upper surface of the side wall of the plate 2, to prevent downward movement of the key; the thickened body portion of the key between the head 13, 100 and lug 14, being adapted to rest in contact with the outer side face or surface of the plate 2, as clearly shown in Fig. 2. The upper and thinner portion of this key 8, is of a resilient character, and at its extreme upper portion 105 is provided an inwardly projecting pointed head or hook 15. The securing key 7, is also made of steel, and a portion of its outer side

is provided with a series of ratchet teeth 11, and at the extreme upper end of the key is a laterally projecting head.

In applying the securing locking keys 7 and 8, the key 8 is first passed through one of the openings 10, in the plate 2, so that the head 13, and lug 14, contact with the upper and lower portions of said plate 2; the key 7 is now inserted in one of the recesses 6 in the 10 fish plate and back of the key 8, and then driven downward and through one of the openings in the plate 2. During the downward movement of this key 7, the inclined face of the recessed portion of the fish-plate 15 forces the outer surface of said key against the inner surface of key 8, thus securing the latter in its proper position at all times, and the resilient hook-shaped head 15 will spring forward and engage the ratchet teeth 11 to 20 prevent upward movement of the key 7. The resilient character of the upper portion of the key 8, and its beveled hook-shaped head 15, permits said head to ride over the ratchet teeth 11, as the key 7 is driven downward, but when the said key 7 is at rest the head 15 will spring inward and engage one of 25 said teeth 11. If desired the key 7 may be slightly wedge-shaped below the toothed portion thereof, to exert a greater binding 30 and clamping effect on both the key 8 and fish-plate.

While I have shown my improved joint in connection with wooden railway ties, it will be readily perceived that, by modifying the 35 means for securing the plate 2 to the ties the joint may be utilized in connection with metal ties without any change whatever with reference to the essential parts embodied in my invention.

40 It will be obvious that the upper surface of the ties may be so recessed that the upper surface of such portions of plate 2, as is adapted to be seated on the ties will rest flush with the upper face of said ties.

45 It will be understood that slight alterations in the precise details herein described may be resorted to without departing from the spirit of my invention.

Having thus described my invention, what I claim and desire to secure by Letters Patent is:

1. A railway rail joint, comprising a combined base and bridge-plate having upward projecting side walls, said plate being adapted to receive and support the end portion of two rails between said side walls, fish-plates fitted between the side walls and resting in contact therewith, and securing keys fitted in recesses in the fish-plates and openings in the bridge-plate, one of said keys engaging the other, substantially as described.

2. A joint for the meeting ends of two rails, comprising a base plate provided with openings therethrough, a fish-plate on each side of said rails, each fish-plate having a plurality of recesses, a securing key fitted in each of said recesses, and a locking key fitted to the base plate and adapted to interlock with said securing key, both keys being fitted in said openings in the base plate.

3. A joint for the meeting ends of two rails, comprising a base plate provided with openings therethrough, a fish-plate on each side of said rails having a plurality of recesses in the inclined face thereof, a securing key 75 fitted in each recess, said key being provided with a series of ratchet teeth, and a resilient locking key, the upper portion of which is adapted to engage said ratchet teeth, both of said keys passing through an opening in the 80 base plate.

4. A joint for the meeting ends of two rails, comprising a base plate, a fish-plate on each side of said rails having a plurality of recesses in its outer face, a securing key provided with a series of ratchet teeth fitted in each recess, and a locking key provided with outwardly extending lugs and a resilient upper portion the upper end of said resilient portion engaging the ratchet-teeth on said 90 securing key, substantially as described.

EZRA C. ALE.
